UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.
GAS-PRODUCER.

1,251,011.

Specification of Letters Patent. Patented Dec. 25, 1917.

Application filed February 6, 1915. Serial No. 6,487.

To all whom it may concern:

Be it known that I, JEROME R. GEORGE, a citizen of the United States, residing at Worcester, in the county of Worcester and 5 Commonwealth of Massachusetts, have invented a new and useful Improvement in Gas-Producers, of which the following, together with the accompanying drawings, is a specification.

10 The present invention relates to gas producers, and has particular reference to that class of producers which embody a rotatable support for the ashes, spaced beneath the body portion of the producer, the bottom of 15 said ash support having a radial scraper or plow resting thereon. When desired, said plow may be held stationary with respect to the rotating support, thereby causing the ashes to be crowded outwardly and delivered over the edge of said support.

Various mechanisms have been employed to inaugurate the plowing or crowding action of said scraper, by the interposition of a fixed stop in the path of the same; and 25 for interrupting said crowding action after a predetermined period of activity, by withdrawing said stop, thereby permitting the rotation of the scraper in unison with the ash support. A mechanism of this character is fully set forth and described in the 30 Letters Patent to Jefferies, No. 1,198,087, granted September 12, 1916, the same providing a weighted arm or pawl, adapted to be moved from its normal position by an 35 attendant, when it is desired to bring about a discharge of ashes from the support. The rocking of said pawl brings about the action of certain mechanism which insures the subsequent retention of the plow in a fixed position for a predetermined period; thereafter 40 the parts are automatically returned to their normal positions, and the discharge of ashes is discontinued until the attendant again rocks the pawl whereupon the above 45 described operations are repeated.

The present invention is concerned with the provision of means whereby the desired discharge of ashes from a gas producer is removed from the necessity for any action 50 on the part of an attendant, resulting from the exercise of his judgment as to the proper times for such intermittent discharges to take place, during the continuous operation

of the producer. Instead it is proposed to utilize the presence of varying thicknesses 55 of fuel in the chamber of the producer, as the agency for determining the periods of operation of the ash discharging mechanism; it being clear that since the proper operation of the producer is best served by 60 maintaining, as near as possible, a substantially constant level for the surface of the fuel bed, the discharge of ashes, if made responsive to the attainment of an excessively high level of fuel in the producer, caused 65 either by an excessive accumulation of ash, or by an overfeed of fresh fuel, acts to restore the fuel bed to its most efficient working conditions.

The mechanism by means of which the 70 above and other objects are attained is fully set forth in the following description, reference being had to the accompanying drawings, in which—

Figure 1 is a side elevation of a gas producer having my invention applied thereto.

Fig. 2 is a vertical sectional view of a portion of the apparatus.

Fig. 3 is a detail view of the latching mechanism for stopping the rotation of the 80 scraper.

Fig. 4 is a fragmentary view similar to Fig. 1, showing the parts in a different position, and

Figs. 5 and 6 are detached views of the 85 mechanism employed for automatically releasing the ash scraper.

Similar reference characters refer to similar parts in the different figures.

In carrying out my invention I propose 90 to transmit the variations in the level of the fuel bed to the mechanism for starting and stopping the action of the ash plow by the use of a device which is at all times responsive to such variations, such a device 95 being embodied in the fuel leveling mechanism shown and described in the pending joint application of Charles W. Lummis and George H. Isley, Serial No. 840,110, filed May 21, 1914, and consisting of a pivoted member, inclined to the vertical, with its free end supported upon the surface of the fuel bed, which latter is subject to constant rotation in order to bring all portions of said surface under the influence of 105 said member.

Accordingly, I have shown in Figs. 1, 2 and 4, a gas producer comprising a main or fuel section 1 inclosing a gas producing chamber, said fuel section being rotatable by any suitable mechanism. The fuel section is connected to and spaced above a rotatable ash support 4, consisting, in the present instance, of a shallow pan into which the ashes are delivered from the fuel section of the producer through the open bottom of the same. The ash support is mounted upon rollers 5, 5 and is rotated by a rotating pinion 6 engaging an annular rack 7 upon the ash support. It is to be understood, however, that my invention is not to be limited to the specific means herein illustrated for rotating the fuel section and the ash support; since it is possible to rotate said elements in unison from separate actuating devices, as will be clearly understood. Above the rotating fuel section 1, and supported by the standards 8', I provide a stationary cover section 8, upon which the mechanism hereinafter described finds support, said cover section affording an outlet for the gases from the gas producing chamber in the usual manner.

In accordance with the invention of the said Jefferies, there is journaled concentrically within the rotating ash support 4 an ash plow or scraper 9, resting upon the bottom of said ash support and consisting, in the present instance, of a helical shaped arm having its outer or free end 10 arranged to be engaged by a latch 11 pivoted at 12 upon the lower end of an arm 13 extending downwardly from one of the standards 8' toward the ash support. By reason of its frictional engagement with the bottom of the ash support, the scraper 9, when not engaged by the latch 11, rotates with said ash support. The upper end of the latch 11 is connected by a link 14 with a short arm 15 carried upon the inner end of a rocking shaft 16. Attached to the outer end of the rocking shaft 16 is a lever 17 supporting upon its free end an adjustable counterweight 18. The lever 17 is connected by a link 19 with one end of a lever 20 turning loosely upon a shaft 21 supported in brackets 22 upon the cover section 8 of the gas producer.

Journaled upon the shaft 21 is a lever 23 carrying upon one end an adjustable counterweight 24, which is normally supported upon a stop or rest 25 by which the lever 23 is maintained in a horizontal position. The opposite end of the lever 23 is pivotally connected by a link 26 with a radial arm 27 attached to one end of a rocking shaft 28. The opposite end of the rocking shaft 28 carries a radial arm 29 in the free end of which is a cam roll 30. Attached to the outer wall of the ash support 4 is a cam 31, said cam roll 30 being arranged in the path of the cam 31 as the latter is carried around by

the rotatable ash support 4. Extending upwardly from the rocking lever 23 is a short arm 32, upon the end of which is pivotally supported a pawl 33 having upon one end a small counterweight 34 and provided with an arm 35 which carries thereon an adjustable counterweight 36. The lever 20 is provided with a notch 37 adapted to receive the end 38 of the pawl 33, as shown in Fig. 6, upon the operation of the mechanism in the manner hereinafter described.

With the lever 17 in the position shown in Fig. 5, the latch 11 is disposed so as to bring its lower end 39 into the path of the scraper 9, and it will be understood that if said latch be so held, the advancing end 10 of the scraper will be engaged thereby, causing said scraper to be held from rotation. The continued rotation of the ash support with the scraper thus held from rotation carries the mass of ashes against the helical side of the scraper, causing such ashes to be pushed outwardly and crowded over the flaring side of the pan. The movement of the latch 11 into the position shown in Fig. 6 permits the rotation of the scraper 9 with the ash support and consequently interrupts the discharge of ashes from said support. The several movements of latch 11 are controlled by the cam 31 in the following manner:—The cam 31 as it is carried around by the rotating ash support will ride over the cam roll 30, depressing the arm 29 and rocking the shaft 28. The rocking of the shaft 28 through the radial arm 27 and link 26 will rock the lever 23 on the shaft 21 from the position shown in Fig. 1 to that represented in Fig. 5, whereby the pawl 33 which, it will be assumed, has been caused to occupy the position shown in Fig. 4, will tip over to the right, with its end resting against the extreme end of the lever 20, beyond the notch 37 of the latter, as shown in said Fig. 5. When the cam 31 passes the cam roll 30, the counterclockwise 105 motion of the lever 23, restoring it to the position shown in Fig. 1, allowing the end 38 of the pawl 33 to engage the notch 37 in the lever 20. In this position of the pawl 33, the next passage of the cam 31 over the cam roll 30 will again rock the shaft 28, depressing the arm 27 and again rocking the lever 23 through the link 26 into the position shown in Fig. 6. At this rocking movement of the lever 23, however, the engagement of the pawl 33 with the lever 20 will lift the lever 17 through the link 19, thereby rocking the shaft 16 and, through the radial arm 15 and link 14, rocking the latch 11 into the position shown in Fig. 6.

The lifting of the latch 11 into this position permits the passage thereunder of the scraper, provided said scraper is in radial alignment with the cam and arrives adjacent the latch when the latter is in raised position.

tion. If such is not the case, as happens when the device is first put into action, the subsequent arrival of the scraper finds the latch depressed, owing to the movement of the cam 31 past the roll 30. The depressed latch holds the scraper stationary until the cam 31 again engages the roll 30, moving the latch into the position shown in Fig. 6 and permitting rotation of the scraper. Thereafter the cam and scraper rotate together, the latch 11 being raised at each revolution to permit the passage of the scraper thereunder.

By the above described invention of Jef-
15 feries, further removal of ashes is made de-
pendent upon a subsequent rocking of the
pawl 33 toward the left, from the position
shown in Fig. 6 to that shown in Fig. 4.
It follows that when the cam 31 thereafter
20 comes in contact with the roller 30, the lever
23 is moved downwardly, without carrying
with it the lever 20, thereby leaving the latch
11 in position to arrest the rotation of the
scraper. During the revolution of the ash
25 support 4 immediately following, ashes are
therefore discharged, unless there arises a
force tending to move the scraper, sufficient
to raise the counterweight 18, the latter be-
ing made heavy enough to hold the scraper
30 firmly to its work. Should such a force
arise, due to the jamming of a mass of
clinker between the scraper and the wall of
the ash support, or to any other cause, the
35 latch 11 is forced upwardly against the force
exerted by the counterweight 18 and the
scraper continues to rotate until the force is
removed. But unless such abnormal force
arises, the scraper will be held stationary,
40 as before stated, during a single revolution
of the ash support. When the cam again
comes under the roller 30, the pawl 33 has
assumed the position shown in Fig. 6, and
the release of the scraper is effected. The
45 interruption to the discharge of ashes con-
tinues until the pawl is again moved to the
left, from the position shown in Fig. 6 to
that shown in Fig. 4.

The present invention provides for the
50 automatic movement of the pawl 33, from
the inoperative position shown in Fig. 1 to
the operative position shown in Fig. 4,
whereby the above described intermittent
discharge of ashes from the support 4 is
55 made responsive to the presence of an ex-
cessively high level of fuel in the section 1.
To this end there is provided within the
gas producing chamber a member 40 rigidly
60 attached to a rock shaft 41 supported in
journals 42 carried by the stationary cover
section 8. Said member 40 projects down-
wardly through a suitable opening provided
65 in the cover section, to permit of its free
angular movement about the horizontal axis
afforded by the shaft 41, with the free end
of said member resting upon the surface
of the fuel bed in the fuel section 1, and
preferably in an approximately radial dis-
position with respect thereto. By reason of
its pivotal support, it will be seen that the
leveling action of said member is continu-
70 ous with respect to the constantly rotating
fuel beneath the same, irrespective of
changes in the mean level of said bed, since
said member, rising and falling with the
fluctuations of said level, automatically ad-
75 justs itself to all heights of the fuel bed.

The shaft 41 carries a rigid upward pro-
jecting arm 43, having on its free end an ad-
justable weight 44. A link 45, having a
pin and slot connection 46 with an interme-
diate point of the arm 43, is pivotally con-
nected at its other end to a swinging arm
47, pivoted at 48, and carrying between its
ends a weight 49. Between said weight and
its pivotal support 48, said swinging arm 80
has pivotally secured thereto a link 50, the
other end of which is pivotally attached to
the depending arm 51 of a bell crank lever
pivoted, for convenience, upon the shaft 21.
The other arm 52 of said bell crank lever 90
extends substantially horizontally and has
pivoted to its end a link 53, which link at
its other end has an elongated slot 54 re-
ceiving a pin 55 carried by the weight 34 of
the pawl 33.

The operation of the above described
mechanism will be clear from a reference
to Figs. 1 and 4. In Fig. 1 the level of the
fuel in the section 1, indicated by the broken
line 56, is substantially normal, *i. e.*, within 100
the horizontal zone coincident with a thick-
ness of fuel bed best suited to the efficient
operation of the producer. The angular
vibration of the evener 40 in response to
slight variations of this level within the 105
aforesaid zone, is permitted by reason of
the pin and slot connection 46 of the arm
43 with the link 45, the weight 44 on said
arm serving to hold the free end of member
40 in contact with the fuel, and assisting 110
in the leveling action thereof. As the level
of the fuel bed rises, due either to an over
accumulation of ashes in the support 4, or
to an excessive feeding of fresh fuel to the
producer, or to both of the above mentioned 115
causes, the member 40 responds by assum-
ing positions nearer and nearer to the hori-
zontal, the arm 43 approaching nearer and
nearer the vertical, and drawing the link
45 gradually to the left in Fig. 1. The con-
tinuation of this tendency finally carries the
swinging arm 47 and its weight 49, also
moving toward the left, past the vertical
plane containing the axis 48 of said arm,
whereupon said arm drops sharply down 120
by gravity into the position shown in Fig.
4, such movement being permitted by reason
of the lost motion connection between the
link 45 and arm 43. The above described
movement of the arm 47, through the link 125

- 50, rocks the bell crank 51—52 into the position shown in Fig. 4, drawing down the link 53 until the extreme end of the slot 54 rocks the pawl 33 past its position of dead 5 center, whereupon said pawl drops by gravity into the position shown in Fig. 4. As heretofore described, the mechanism is now in a condition to automatically interpose the latch 11 in the path of the scraper 10 and to retain said scraper stationary during a single revolution of the ash support, thereby effecting the discharge of ashes therefrom and causing the desired lowering of the surface of the fuel bed. At the end of 15 such revolution, the engagement of the cam 31 with the roller 30 in the manner previously described, causes the disposition of the pawl 33 in the ash discharge interrupting relation of the parts, shown in Fig. 6. 20 At the same time, the lowering of the level of the fuel bed, due to the discharge of ashes described above, enables the member 40 and weighted arm 43 to restore the several connecting links, arms and levers to the 25 position shown in Fig. 1, from the position shown in Fig. 4, such restoration being effected through gravity, by the preponderance of weight of said arm 43, weight 44 and member 40, over the arm 47, weight 49 30 and the linkage carried by said arm.

I claim.

1. In a gas producer, an ash support, and means operable with respect to said ash support for discharging ashes therefrom, the 35 operation of said means being responsive to changes in the level of the fuel bed in the producer.
2. In a gas producer, an ash discharging mechanism adapted to be rendered operative and inoperative, and means responsive to changes in the level of the fuel bed in the producer for causing the operation of said mechanism.
3. In a gas producer, an ash support, an 45 ash scraper operable with respect thereto to discharge ashes therefrom, means responsive to changes in the level of the fuel bed in the producer for effecting the operation of said scraper, and means for interrupting 50 the operation of said scraper after a predetermined period of activity.
4. In a gas producer, a rotating ash support, a scraper capable of rotation with said support, means responsive to changes in the 55 level of the fuel bed in said producer for checking the rotation of said scraper, and means actuated by the rotation of said ash support for releasing said scraper from said checking means.
5. In a gas producer, a rotating ash support, a scraper capable of rotation with said support, means operable by a rise in the level of the fuel bed in said producer for automatically interposing a stop in the path of 60 said scraper to prevent its rotation with 65 said support, and automatic means for withdrawing said stop from the path of said scraper.
6. In a gas producer, a rotating ash support, a scraper resting on the bottom of 70 said ash support, means responsive to changes in the level of the fuel bed of the gas producer for holding said scraper stationary during a predetermined period in the rotation of said support, and means actuated by the rotation of said support for rendering said holding means inoperative. 75
7. In a gas producer, a rotating ash support, a scraper capable of rotation with 80 said ash support, a latch adapted to be interposed in the path of said scraper; means for withdrawing said latch from said path when the scraper is carried into juxtaposition thereto, and means responsive to changes in the level of the fuel bed in the 85 producer for rendering said withdrawing means inoperative.
8. In a gas producer, an ash support, a scraper adapted to coact with said support to effect the discharge of ashes therefrom, 90 means operable by a rise in the level of the fuel bed in said producer for automatically inaugurating the action of said scraper, and automatic means for interrupting the action of said scraper. 95
9. In a gas producer, a rotating ash support, an ash scraper therein, means responsive to changes in the level of the fuel bed in the producer for holding said scraper stationary with respect to said support, and automatic means for releasing said scraper. 100
10. In a gas producer, an ash discharging mechanism, a gravity actuated device for inaugurating the action of said mechanism, and means responsive to changes in the level of the fuel bed in the producer for rendering said device operative. 105
11. In a gas producer, an ash discharging mechanism, gravity actuated devices for initiating the action of said mechanism, and gravity actuated means for restoring said devices to normal position after the operation of said ash discharging mechanism. 110
12. In a gas producer, an ash discharging mechanism, means actuated by a rise in the 115 level of the fuel bed in the producer beyond a predetermined height for inaugurating the action of said mechanism, and means for interrupting the action of said mechanism after a predetermined period of activity. 120
13. In a gas producer, an ash discharging mechanism, a member adapted to be moved into a predetermined position, whereby to inaugurate the action of said mechanism, means actuated by a rise in the level of the 125 fuel bed beyond a predetermined height for moving said member into said predetermined position, and means for automatically

restoring said member to normal position after a predetermined period of activity of said discharging mechanism.

14. In a gas producer, an ash discharging mechanism, a fuel leveling member adapted to change its position in response to changes in the level of the fuel bed in the producer, and means operatively connecting said

mechanism and said member, whereby the action of said mechanism is controlled by the position of said member.

Dated this first day of February, 1915.
JEROME R. GEORGE.
